ARTHUR E. PEW, JR., OF BRYN MAWR, AND HENRY THOMAS, OF RIDLEY PARK, PENNSYLVANIA, ASSIGNORS TO SUN OIL COMPANY, OF PHILADELPHIA, PENNSYLVANIA, A CORPORATION OF NEW JERSEY

APPARATUS FOR CRACKING MINERAL OIL

Application filed June 26, 1929. Serial No. 373,703.

In an application filed August 18, 1928, Serial No. 300,441, of which this application is in part a continuation, we describe a process and apparatus for cracking mineral oil. The apparatus comprises a boiler, adapted to generate mercury vapor, connected, by outflowing vapor lines and by back-flowing condensate lines, with a plurality of tanks, each of which contains a coil through which flows the oil that is to be heated and cracked. The coils of the several heating units are arranged in series. In each heating unit, heat exchange with the oil effects condensation of the mercury vapor, the condensate returning to the boiler through the back-flow connection.

The use of mercury vapor as a heating medium involves grave danger of serious results due to any rupture of a coil while the oil, under high pressure, is flowing therethrough in heat exchange relation with the surrounding mercury vapor. No such system can be said to be of any practical value, or to possess commercial possibilities, unless adequate safeguards are provided to prevent such results from accidents of this character. The object of the invention is to provide an apparatus containing all the provisions and safeguards required to make the process safe as well as economical and efficient.

In the drawings:

Fig. 1 is a diagram of the cracking units, their connections with the mercury boiler, and the conduits for mercury flow and mixed oil and mercury flow as hereinafter described.

Fig. 2 is a view, in side elevation, partly broken away, of one of the heating units, whose construction forms the subject-matter of Letters Patent No. 1,794,200, issued to us February 24, 1931.

Fig. 3 is a detail view of one of the automatic non-return valves.

The cracking apparatus, per se, comprises four tanks *a*, *b*, *c*, and *d*, in each of which is a coil of pipe *e*. The oil to be cracked flows through the coils of any three of the tanks in series. For example, the oil may flow through line 4 and hence through the pipe coil in tank *a*, thence through pipe 5 and through the coil in tank *b*, thence through

pipe 6 and through the coil in tank *c* (in which the cracking is completed), and thence through pipe 9 and line 10. The pipes leading to and from the heaters are so arranged that any one of the tanks may be by-passed by the oil stream. In the example given, the tank *d* is by-passed. By proper valve manipulation, either of tanks *a*, *b* and *c* may be by-passed. For example, if tank *a* is by-passed, the oil flows from line 4 into pipe 5, thence through tanks *b* and *c* as above described, and thence through pipe 7, tank *d* and pipe 8 to line 10.

The described arrangement of four tanks of which any three may be in operation simultaneously permits the continuous operation of the plant. When it is desired to clean out the pipe sections of any coil *e*, it is by-passed and the previously by-passed coil is placed in series with the other two coils.

Mercury vapor from boiler *z* flows through line 80 and thence, in parallel, through branch pipes 81 into the several tanks that are in operation. Mercury vapor enters each tank at the top. Condensed mercury flows out from the bottom of each tank through pipes 82 and 83 into a clean-out 84. This clean-out communication, top and bottom, with one of the balancing columns of mercury 85, the other balancing column communicating with a line 86 flowing into a clean-out 87, which communicates top and bottom, with a stand pipe 88, the bottom of which connects, through pipe 89, with the liquid mercury space of the boiler.

By throttling more or less the valves 90 on the mercury vapor inflow pipes 81, the pressure of mercury vapor in any given tank may be reduced in varying degree below boiler pressure, thereby making it possible to predetermine the temperature of condensation in each tank independently. The difference between the pressures in the boiler and in a given tank will be taken care of by a corresponding difference in the levels of mercury in the two columns 85. It will thus be understood that by providing a boiler pressure sufficient to give a vapor temperature above the maximum temperature of con-

55

densation that may be desired in any of the tanks, any desired temperature of condensation may be established in any of the tanks. Thus extraordinarily exact temperature control is achieved, which is of the utmost importance, as will be explained hereinafter.

In order to limit the maximum boiler pressure, a pipe 91 from the mercury vapor feed or supply line 80 extends through a condenser 92 to a clean-out 94. On pipe 91 is a loaded safety valve 93. The clean-out is connected, top and bottom, with a mercury seal 95, which connects with the mercury condensate return flow line 86.

15 The described means for maintaining a constant boiler pressure and for governing the pressure in each tank is more particularly described in Letters Patent No. 1,714,811 and No. 1,714,812, issued to us May 20 28, 1929.

In the application of which this is in part a continuation we have shown and described the flow of charging stock through heat exchangers to the line 4. We have also shown 25 and described the flow of cracked stock through line 10 and the method and means for separating the gasoline therefrom. These features of the complete cracking plant form no part of the present invention and are not 30 herein shown and described. For purposes of illustration it may be assumed that the charging stock enters line 4 at a temperature of (say) 435° F., that it may be heated gradually or quickly in the first coil or in successive coils to a temperature of 865° F., that 35 this temperature, once attained, may be maintained in the coils, or may be slowly raised or otherwise varied, until the cracked stock flows out through line 10. There is, of course, 40 a drop in pressure during the flow of the oil through the heat exchanger (not shown) before it enters line 4 and a very considerable drop in pressure during the flow of oil through the cracking coils. Thus the initial- 45 ly imposed pressure on the oil may be assumed, for purposes of illustration, to be 1200 pounds to the square inch and that before the oil reaches the pressure relief valve (not shown) on line 10 the pressure may be reduced to 650 pounds per square inch. To 50 heat the first heating or cracking unit through the temperature range 435-865° F. and maintain it at the higher temperature during the remainder of its flow through that unit would 55 require a mercury temperature of 866° F. or thereabouts. To maintain the temperature of the oil at 865° F. during its flow through the other units would require a mercury temperature of about 875° F. The pressure in 60 pounds absolute of mercury vapor at 875° F. is about 80. Accordingly the boiler may operate at 80 pounds pressure, or at a somewhat higher pressure if the temperature is to be raised above 865° F. during the flow of 65 the oil through the coils.

The above data are given merely to illustrate the great difference in pressures to which the mercury and the oil are subjected. It is obvious that, without special safety contrivances, if a coil should be ruptured, conditions would be created that would produce serious and even disastrous results. The shell of the tank would be subjected to a pressure far beyond that which it is intended to resist. Even if the shell should be made capable (which is practicable) of resisting the vastly increased pressure, the oil and oil vapors would flow toward and into the boiler through the mercury vapor and mercury condensate lines and contaminate the whole mercury vapor system, which, including the boiler, would be subjected to an immensely increased pressure, with disastrous results.

Our invention comprises means, in the event of tube failure, to prevent serious rise of pressure in the tank and, particularly, in any other part of the mercury vapor system, to prevent contamination of the mercury vapor system with oil, to limit the amount of oil that will escape into the tank, to segregate any mixture of oil and mercury that will necessarily result from the escape of a limited amount of oil from the ruptured coil and to separate and recover the mercury from the mixture, to shut off the flow of oil into the broken coil, to prevent a back flow of oil from a coil ahead into the broken coil, and to in effect isolate the unit in which the accident occurs from the remainder of both the mercury system and the oil system and insure against any serious injury even to the isolated unit. The contrivances which we have provided to insure these measures of safety are of necessity wholly, or largely, automatic, but these automatically operating devices are supplemented by manually operable valves which are operable at any time and which, therefore, are operable to supplement the action of the automatic devices.

Before describing the safety devices in detail, there should be a description of the preferred construction of a heating unit.

The tank containing a coil *e* comprises a shell having circular dished end heads *r* and *s*, and has openings at the top communicating with the mercury vapor inflow pipes 81, and a connection at the top with a pipe 96 on which is a relief valve 97 to relieve internal pressures. The pipe sections forming the coil are, at one end, welded to head *r* from either the inside or outside and are connected one to another by headers or return bends *g*, which are removable for cleaning purposes. Inside the tank, near the other end, is welded a ring of steel *t*, which has been machined. A circular box *u*, with flat heads, is inserted inside the steel ring. The other ends of the pipe sections are welded to the inside head of box *u*, and headers or return bends *v* connect adjacent pipe sections and, like headers

q, are removable. Welded to the other head of box *u* is a pipe or neck *w*, which extends out through head *s* and is welded thereto. At the outer end of neck *w* are two flanges 5 *x* bolted together to make a tight connection. Installed in neck *w* is an expansion joint *y* of the well known accordion type.

- Mercury vapor fills the space around the tubes composing the coil *e* but cannot penetrate the box *u*. It is thus possible, without hazard, for a man to enter box *u* through neck *w* and remove the return bends *v* when the tank is not in operation. Mercury vapor, however, will penetrate, through the sliding 10 fit between box *u* and ring *t*, the space between box *u* and end head *s*. Such vapors condense and are withdrawn through pipe 83. The main condensate flows out through line 82.
- 20 In case any of the pipe sections of any coil *e* should break, provision should be made to prevent oil vapors from flowing to the boiler either through the mercury vapor line or through the mercury condensate line. A 25 number of provisions are made to insure against this possibility.

As before stated, at the top of each mercury vapor tank is a pipe 96 equipped with a safety valve 97, which is set for any desired pressure, say 125 pounds. The pipes 96 leading from the several tanks connect with a common pipe line 98, which extends through a cooler 99 into a steel tank 100. In case a tube breaks, safety valve 97 opens 35 as soon as the pressure rises to 125 pounds and the mixture of oil vapors and mercury vapor are cooled in cooler 99 to a temperature of (say) 450° F., the mercury and most of the oil being thus liquefied. The liquid 40 mercury, oil and oil vapors then enter tank 100. Due to the difference in the specific gravities of mercury and oil, the mercury collects in the conical bottom and may be drawn off.

45 The mercury seals 85, hereinbefore described, are of sufficient depth to hold a pressure in excess of 125 pounds and, therefore, in event of tube failure, would prevent oil from flowing to the mercury boiler through 50 the mercury condensate return 86. Any liquid oil or oil vapors that would enter pipe 82 would be trapped in the clean-out 84, due to the mercury seal 85.

55 In the event of tube failure, oil vapors are prevented from flowing to the mercury boiler, by way of the mercury vapor inflow pipe 81 and inflow line 80, by means of the lower valve 30 on pipe 81. This valve is a non-return valve that closes in case the pressure in the tank exceeds the pressure in line 80. As a double safeguard, the upper valve 90 may be a remote control hand operated valve. 60

65 While the above provisions insure against the contamination of the mercury system with oil in case of tube failure, provision is also

made to limit the amount of oil that would escape into the tank. To this end valves are installed which automatically isolate any heating tank in which a tube breaks. The valves are arranged in pairs, 31, 32, 33, 34, 70 35, 36, 37, 38 and 39. Of each pair of valves, one valve is an automatic valve and the other a hand operated valve with remote control for safety; the automatic valve being adapted to close when the pressure drops below a fixed point. Valves 41, 42, 43, 44 and 45 are operated in order to by-pass any unit. Let it be assumed that the plant is operating on units *a*, *b* and *c* and that a break occurs in unit *a*. This would result in an immediate 75 drop in pressure in line 4; and the two automatic valves of the two pairs of valves 31 and 32 would immediately shut, preventing further flow of oil into unit *a*. By suitable connections from these valves to the power 80 shut-off on the high pressure pump (not shown), this pump would stop. The other two valves of the two pairs of valves 31 and 32 would then be closed by hand.

To prevent oil from backing up into the 90 unit in which a break has occurred from the unit immediately in advance, one of the valves of each pair of valves 33, 35, 37 and 39 is made a check valve, the other valves of 95 these pairs being hand operated remote control valves for double safety.

It will thus be clear that in case of a break 100 in any of the coils *e*, the corresponding unit is shut off both at the oil inlet and the oil outlet.

On the assumption that units *a*, *b* and *c* are in operation, valves 41 and 42 are shut, they being used only as by-pass valves. If, as above assumed, a break occurs in unit *a*, the check valve of pair 33 closes, preventing 105 oil from backing up from unit *b* into the broken coil in unit *a*.

By reason of the described closing of the automatic valve of the two pairs of valves 31 and 32 and of the closing of the check 110 valve of the pair of valves 33, the inflow of oil to all three units is shut off.

It will thus be understood that if a break occurs in any of the units, there is no automatic diversion of the oil to the other units. 115 All the cracking units are rendered inoperative.

The plant can be restarted by putting in 120 series with the other two units that have been in operation, the unit which theretofore has not been inoperative. Thus, on the assumption that a break has occurred in unit *a* and that all the units are rendered inoperative as described, units *b*, *c* and *d* can be put into 125 operation by closing the hand valve of the pair of valves 32 and the hand valve of the pair of valves 33 and opening the hand valve 41.

The automatic non-return valves hereinbefore mentioned may have any suitable con- 130

struction. One practicable construction is shown in Fig. 3. The stem of the automatic non-return valve 31 is secured to a diaphragm 20, which, through a pipe 22, is subjected to the pressure on the down-stream side of line 4; this pressure holding the valve open against the action of a spring 21 coiled about the valve stem. Should the pressure on the down-stream side fall below the pressure on the up-stream side the spring closes the valve. As soon as the valve shuts, the pressure on the up-stream side rises but cannot pass through the valve.

What we claim and desire to protect by Letters Patent is:

1. An apparatus for cracking oil comprising a tank provided with an inlet for a vaporous heating medium adapted to condense therein under relatively low pressure, a pipe coil extending through the tank for conveyance of the oil to be heated while subjected to relatively high pressure, an outlet from said tank and a safety valve on said outlet set to open, in the event of breakage of the coil, at a pressure between the pressures specified, a pipe connection for carrying away the mixture of heating medium and oil that escapes through said valve, and means interposed in the pipe connection for cooling the escaped mixture and condensing the vaporous heating medium, and means beyond the cooler for separating the condensed heating medium by gravity.

2. An apparatus for cracking oil comprising a tank provided with an inlet for a vaporous heating medium adapted to condense therein under relatively low pressure, a pipe coil extending through the tank for conveyance of the oil to be heated while subjected to relatively high pressure, a source of supply of heating medium, a pipe connection from said source of supply to said inlet and a non-return valve in said pipe connection adapted, in the event of coil breakage and consequent rise of pressure in the tank and escape of oil thereinto, to close said valve and thereby prevent backflow of oil through said pipe connection to the source of supply of heating medium.

3. An apparatus for cracking oil comprising a tank provided with an inlet for a vaporous heating medium adapted to condense therein under relatively low pressure and with an outlet for condensate, a source of supply of heating medium communicating with said inlet and outlet, a pipe coil extending through the tank for conveyance of oil to be heated while subjected to relatively high pressure, and means to prevent escape of oil through said inlet and outlet to the source of supply upon breakage of the coil and consequent escape of oil into the tank and rise of pressure therein.

4. An apparatus for cracking oil comprising a tank provided with an inlet for a vaporous heating medium adapted to condense

therein under relatively low pressure, a pipe coil extending through the tank for conveyance of the oil to be heated while subjected to relatively high pressure, an outlet from said tank, a safety valve on said outlet set to open at a pressure between the pressures specified, a source of supply of heating medium communicating with said inlet, and means, operative in the event of coil breakage and a consequent rise of pressure in the tank and escape of oil thereinto, to prevent back flow of oil through said inlet to said source of supply of heating medium.

5. An apparatus for cracking oil comprising a tank provided with an inlet for a vaporous heating medium adapted to condense therein under relatively low pressure and with an outlet for condensate, a source of supply of heating medium communicating with said inlet and outlet, a pipe coil extending through the tank for conveyance of oil to be heated while subjected to relatively high pressure, and means to prevent escape of oil through said inlet and outlet to the source of supply upon breakage of the coil and consequent escape of oil into the tank and rise of pressure therein, said means comprising a non-return valve in said inlet connection and a liquid seal in said outlet connection.

6. An apparatus for cracking oil comprising a tank provided with an inlet for a vaporous heating medium adapted to condense therein under relatively low pressure, with an outlet for condensate and with another and normally closed outlet, a pipe coil extending through the tank for conveyance of the oil to be heated while subjected to relatively high pressure, a source of supply of heating medium communicating with said inlet and the first outlet and safety devices adapted to operate in the event of breakage of the coil and consequent rise of pressure in the tank; said safety devices comprising means to prevent flow of oil through said inlet and outlet to the source of supply and means to open said normally closed outlet.

7. An apparatus for cracking oil comprising a tank provided with an inlet for a vaporous heating medium adapted to condense therein under relatively low pressure, with an outlet for condensate and with another and normally closed outlet, a pipe coil extending through the tank for conveyance of the oil to be heated while subjected to relatively high pressure, a source of supply of heating medium communicating with said inlet and the first outlet and safety devices adapted to operate in the event of breakage of the coil and consequent rise of pressure in the tank; said safety devices comprising a liquid seal in the outlet connection to said source adapted to hold a predetermined pressure substantially in excess of the normal pressure in the tank, and a safety valve controlling the normally closed outlet and adapted to open

under a pressure substantially in excess of the normal pressure in the tank but below the pressure which said liquid seal is adapted to hold.

5 8. An apparatus for cracking oil comprising a tank provided with an inlet for a vaporous heating medium adapted to condense therein under relatively low pressure, with an outlet for condensate and with another 70 and normally closed outlet, a pipe coil extending through the tank for conveyance of the oil to be heated while subjected to relatively high pressure, a source of supply of heating medium communicating with said inlet and 75 the first outlet, and safety devices adapted to operate in the event of breakage of the coil and consequent rise of pressure in the tank; said safety devices comprising a non-return valve in the inlet connection to said source, 80 a liquid seal in the outlet connection to said source adapted to hold a predetermined pressure, and a safety valve adapted to allow the escape of mixed oil vapor and heating medium through said normally closed outlet, 85 said safety valve adapted to open under a pressure substantially exceeding the normal pressure in the tank but below the pressure which said liquid seal is adapted to hold.

9. An apparatus for cracking oil comprising 90 a plurality of tanks adapted to receive and condense a heating medium under a relatively low pressure, coils, arranged in series, in the respective tanks, for conveyance of the oil to be heated under a relatively high pressure, and a valve on the connection between adjacent coils adapted, upon breakage of the first of two adjacent coils and the consequent reduction in pressure therein, to close and thereby prevent the oil in the coil immediately ahead of the broken coil from backing into the broken coil, and means to maintain flow of oil through the coil ahead of the broken coil while flow of oil to the latter is shut off.

10. An apparatus for cracking oil comprising a plurality of tanks adapted to receive and condense a heating medium under relatively low pressure, coils, arranged in series, in the respective tanks, for conveyance of the oil to be heated under a relatively high pressure, an oil supply pipe leading to the first coil of the series, a valve on said supply pipe, and a valve on the connection between each two adjacent coils, the 110 valves ahead of and behind each coil being adapted to close when the pressure in said coil drops due to breakage of the coil, thereby isolating the broken coil and cutting off the flow of oil thereto, and means to maintain flow of oil through the remaining coils while the broken coil is so isolated.

11. An apparatus for cracking oil comprising a tank provided with an inlet for a vaporous heating medium adapted to condense therein under relatively low pressure,

with an outlet for condensate and with another and normally closed outlet, a pipe coil extending through the tank for conveyance of the oil to be heated while subjected to relatively high pressure, a source of supply of heating medium communicating with said inlet and the first outlet and safety devices adapted to operate in the event of breakage of the coil and consequent rise of pressure in the tank; said safety devices comprising means to prevent flow of oil through said inlet and outlet to the source of supply, means to open said normally closed outlet, and means to shut off flow of oil into the broken coil.

12. An apparatus for cracking oil comprising a plurality of tanks adapted to receive and condense a heating medium under a relatively low pressure, coils, arranged in series, in the respective tanks, for conveyance of the oil to be heated under a relatively high pressure, each tank having an inlet for heating medium, an outlet for condensate and another and normally closed outlet, a source of supply of heating medium communicating with said inlet and the first named outlet, and safety devices adapted to operate in the event of breakage of a coil and consequent rise of pressure within the tank; said safety devices comprising means to prevent flow of oil through said inlet and outlet to the source of supply, means to open the normally closed outlet, and means to isolate the broken coil by shutting off inflow of oil to said coil and back flow of oil into said coil.

In testimony of which invention, we have hereunto set our hands, at Philadelphia, Pennsylvania, on this 22nd day of June, 1929.

ARTHUR E. PEW, JR.
HENRY THOMAS.
